UNITED STATES PATENT OFFICE

SIMON SCHAPIRO, OF NEW YORK, N. Y.

TWO-SIDED WINDOW-CLEANING DEVICE

Application filed October 17, 1928. Serial No. 312,965.

The invention relates generally to cleaning devices and has more particular reference to a novel type of window cleaning device.

The invention has for an object the provision of a device of the class mentioned which is of simple durable construction, desirable in use and efficient in action, and which can be manufactured and sold at a reasonable cost.

10 The invention proposes the use of a U-shaped tube consisting of an inner arm for being disposed on the inner side of a window sash and an outer arm. A stiff flexible cable is slidably mounted in the tube, and arranged 15 for moving a window contact member. The window contact member should be provided with a rubber squeegee and a moistener. The inner arm should be formed with a slot thru which a handle extends, said handle being 20 connected with the cable for moving it.

It is pointed out that a person standing within a room may place the device so that the inner arm is disposed on the inside of a window while the outer arm extends around the 25 outer side. Then the handle may be reciprocated up and down for causing the window contact member to move similarly. Thus the outer sides of the windows may be cleaned without the necessity of a person reaching the 30 outside of the window. This arrangement would prevent the accidental falling of a person attempting to clean the outer sides of the window.

For further comprehension of the invention, and of the objects and advantages thereof, reference will be had to the following description and accompanying drawings, and to the appended claims in which the various novel features of the invention are more particularly set forth.

In the accompanying drawing, forming a material part of this disclosure:—

Fig. 1 is a fragmentary perspective view of a wall with a window and the device applied.

Fig. 2 is a side elevational view of the window cleaning device.

Fig. 3 is an end view thereof.

Fig. 4 is a view similar to Fig. 2, but certain parts being in section.

Fig. 5 is an enlarged detail view of a portion of Fig. 4.

Fig. 6 is a horizontal sectional view, taken on the line 6—6 of Fig. 2.

Fig. 7 is a fragmentary vertical sectional view of the window contact member used in the device.

Fig. 8 is a perspective view of the top end of the rod for supporting the window contact member.

Fig. 9 is a view similar to Fig. 3, but illustrating a modification.

The reference numeral 10 indicates generally a wall of a room, provided with a window frame 11 having an inner sash 12 and an outer sash 13. A window cleaning device 14 is shown engaged about the outer sash 13.

This window cleaning device 14 consists of a U-shaped tube 15, preferably of galvanized iron and having an inner arm 16 and an outer arm 17. As seen in Fig. 1, the inner arm 16 is disposed on the inner side of the sash 13, while the outer arm 17 is disposed on the outer side of the sash.

A flexible stiff cable 18, preferably of brass is slidably arranged within the inner arm 16 and extends the full length of this arm and around the bend of the U-shaped member. A cable handle 19 is attached onto the cable 18 and projects out of a slot 20 formed in the inner arm 16. A rod 21, preferably of brass is slidably mounted in the outer arm 17 and is attached at its lower end onto the cable 18. The top end of the rod 21 extends out of the top of the outer arm 17. Said outer arm has an inturned top edge 22 forming a bearing for the rod 21. A set screw 23 projects from the rod 21 and passes thru a second slot 24 formed in the outer arm 17. This set screw prevents the rod 21 from turning but does not interfere with the sliding of the rod.

A window contact member 24' is attached on the extended end of the rod 21. An end cap 25 is threadedly engaged on the free end of the inner arm 16 for closing the top of this arm. The rod 21 is provided with a front niche 26 and a rear niche 27. A set screw 28 engages thru a flange 29 of the window contact member 24' and engages one of these 100

niches for holding the member 24' in position.

The window contact member 24' consists of a water receptacle 30 having a plug opening 31. A rubber squeegee 32 is engaged in one side of the receptacle and a felt moistener 33 in the other side. Water within the receptacle may touch the rear side of the moistener 33.

10 In the modified form of the device illustrated in Fig. 9 the inner arm 16 is formed with a parallel slot extension 34 connected with the slot 20 by a transverse slot connector 35, and a second parallel slot extension 36 connected with the slot 20 by a second transverse slot connector 37. The slots 34 and 35 are of different lengths and at different height positions relative to the slot 20.

In operation of the device it is placed upon 20 a window sash so that the inner arm is disposed on the inside of the sash and the outer arm on the outside. Then the cable handle 19 is moved up and down in the slot 20. This motion is transmitted by the flexible cable 18 to the rod 21 and to the window contact member 24'. This contact member is first arranged with the moistener 33 adjacent the window. Obviously the window contact member moves up and down so that the outside 25 of the window pane is wetted. The device is then lifted into the room and the window contact member 24' turned around so that the rubber squeegee is next disposed on the outer side of the window pane. When the 30 device is again applied upon the window sash motion of the handle will cause the rubber squeegee to dry the outside of the window pane.

The handle 19 may be passed thru the transverse slot 35 and then into the slot extension 34. In this condition the amplitude of the window contact member will be determined by the top and bottom extremities of this slot. In a similar way the handle 19 could be passed 45 thru the slot connector 37 into the slot extension 36. In this condition the amplitude of the window contact member will be determined by the top and bottom extremities of this slot. This is of particular advantage for 50 adjusting the stroke of the device to window panes of different sizes.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what 60 I claim as new, and desire to secure by United States Letters Patent is:—

1. A window cleaning device, comprising a U-shaped tube having an inner and an outer arm for being positioned respectively on the inner and outer side of a window, a flexible

cable slidable within the U-shaped tube and of a length equal to the U-bend and the inner arm, a window contact member above the free end of the outer arm and connected by a rod with the end of the cable directed towards the outer arm, the said inner arm being formed with longitudinal parallel slots of different lengths connected with each other by transverse slots, and a handle for moving the cable extending thru one of said slots and movable into any of the slots for limiting the amount of motion of the cable.

2. A window cleaning device, comprising a U-shaped tube having an inner and an outer arm for being positioned respectively on the inner and outer side of a window, a flexible cable slidable within the U-shaped tube and of a length equal to the U-bend and the inner arm, a window contact member above the free end of the outer arm and connected by a rod with the end of the cable directed towards the outer arm, the said inner arm being formed with longitudinal parallel slots of different lengths connected with each other by transverse slots, and a handle for moving the cable extending thru one of said slots and movable into any of the slots for limiting the amount of motion of the cable, said handle being attached on the cable and movable transversely into any of the longitudinal slots by a twist of the cable.

3. A window cleaning device, comprising a U-shaped tube consisting of an inner arm for being disposed on the inner side of a window, and an outer arm for being disposed on the outer side of a window, a flexible cable within the tube and of a length equal to the U-bend and the inner arm, and slidably engaged in these parts, a handle attached on the cable and extending out of a slot in the inner arm, and engageable in parallel slots formed in the inner arm, and of different lengths, a rod attached on the cable and extending out of the outer arm, and a window contact member attached on the extended end of the rod.

In testimony whereof I have affixed my signature.

SIMON SCHAPIRO.
